UNITED STATES PATENT OFFICE.

HERMAN B. COLLINS, OF FULTON, NEW YORK.

COMMUTATOR-BRUSH.

SPECIFICATION forming part of Letters Patent No. 541,919, dated July 2, 1895.

Application filed January 26, 1895. Serial No. 536,290. (No model.)

To all whom it may concern:

Be it known that I, HERMAN B. COLLINS, of Fulton, in the county of Oswego, in the State of New York, have invented new and useful 5 Improvements in Commutator - Brushes, of which the following, taken in connection with the accompanying drawings, is a full, clear, and exact description.

My invention relates to improvements in 10 commutator brushes and has for its object the production of a device, which permits the commutator to move in opposite directions, is particularly silent in operation, reduces sparking to a minimum, and makes a practical and 15 effective contact even though the commutator is somewhat out of balance and its contact face is more or less irregular; and to this end it consists, essentially, in the general construction and arrangement of the component 20 parts of the brush, all as hereinafter more particularly described and pointed out in the claims.

In describing this invention, reference is had to the accompanying drawings, forming a 25 part of this specification, in which like letters and numerals indicate corresponding parts in all the views.

Figure 1 is an elevation of a pair of my improved brushes and brush holders therefor, 30 shown in section and as operatively mounted upon a supporting rocker arm. Fig. 2 is a horizontal sectional view, taken on line 2—2, Fig. 1. Fig. 3 is an inverted plan view of the detached contact piece of my brush. Figs. 4, 35 5, and 6 are vertical sectional views, taken respectively in lines 4—4 and 5—5, Fig. 1, and line 6—6, Fig. 2. Fig. 7 is a vertical sectional view of a contact piece and a movable body section of slightly modified construction. 40 Fig. 8 is an isometric view of a pair of the detached sections of a modified form of contact piece. Fig. 9 is an isometric view of a further modified form of contact piece and the adjacent end of a supporting body therefor. Fig. 45 10 is an elevation of a pair of brush holders shown in section as operatively mounted upon a supporting rocker arm and as provided with brushes of a still further modified construction. Fig. 11 is an isometric view of the outer 50 end of the movable body section of one of the brushes seen at Fig. 10. Fig. 12 is a detail sectional view, taken on line 12—12, Fig. 10;

and Fig. 13 is an isometric view of one of the detached contact pieces and its retaining lock seen at Fig. 10.

55

A is a rocker arm, and B B brush holders mounted thereon. This rocker arm may be of any desirable form, size, and construction, and is here shown as composed of a split hub a, which is mounted in the usual manner on 60 a supporting spindle, not here illustrated, and oppositely arranged arms a' a' provided with spindles A' A' for supporting the brush holders. The split hub a is secured in operative position by a suitable clamp a² partly shown 65 by dotted lines provided with a screw threaded spindle a³ passed through separated ears a⁴ a⁴ upon said hub. The brush holders B B are also of any desirable form, size, and construction, are loosely mounted on the spindles A' A', and are connected by springs B' B' 70 to arms B² B² fixed to the spindles A' A'. Corresponding ends of the brush holders B B are provided with sockets or apertures b b for receiving the securing ends of the brushes 75 and supporting suitable clamps b' b' for firmly holding said ends in their designed position.

Each of the brushes consists of a contact piece C, and a suitable supporting body c, which preferably consists of separate sections 80 c' c². One side of the contact piece C is formed with a bearing face C' formed concave transversely for making contact with the peripheral face of the commutator D. Shown by dotted lines at Figs. 1 and 10. The face C' is provided with transverse ribs C² which extend 85 between the front and rear edges of the face C' and are preferably arranged with the front end of one rib in proximity to a transverse plane as 1, Fig. 3, drawn through the rear end 90 of the next adjacent rib. These ribs may, however be otherwise arranged, or may be entirely omitted as seen at Figs. 9 and 10.

The opposite or outer face of the contact piece C is detachably hinged to the supporting body c, and preferably to a rocking or revoluble arm c³ extending at substantially right angles with the supporting body c and movable on an axis, as 2, Fig. 1, substantially parallel with the lengthwise plane of said body c. 95 Any suitable joint may be used for connecting the contact piece C to its supporting body, but I preferably use a very simple construction of such a joint, which consists of the nar- 100

row outer portion of the arm c^3 provided with a bearing face c^4 formed convex in cross section, and a lengthwise socket or groove for receiving said narrow portion having its inner face C^4 formed concave in cross section and its side walls C^3 inclined outwardly from each other. The face c^4 may also be formed convex longitudinally, as seen at Fig. 4, or it may be disposed in a substantially flat lengthwise plane as illustrated at Figs. 7 and 12. When the face c^4 is convex longitudinally, and the contact piece consists of separate sections as presently described, portions of the face c^4 corresponding in length to the separate sections are formed convex longitudinally as clearly seen at Fig. 4.

The joint between the contact piece C and its supporting body is interposed between parallel transverse planes as 3—3, Fig. 1 extending substantially perpendicular to a plane projected through the projecting edges of the face C' of said piece, and is arranged substantially parallel with the face C' and the inner face C^4 of the socket or groove in the contact piece, which is the face of said joint nearest the face C' , is arranged somewhat nearer the longitudinal intermediate portion of the face C' , than the opposite projecting edges thereof. This arrangement of the brush prevents its undue tilting, although the brush is free to tilt or rock a sufficient distance to insure a positive and effective contact, even though different portions of the bearing face of the contact piece wear at an unequal rate.

35 A suitable lock E of any desirable form, size, and construction, secures the detachably hinged contact piece C to the arm c^3 , but does not prevent the lateral movement of said contact piece upon its joint with the supporting body c ; and, as clearly illustrated at Figs. 1 and 2, this lock preferably consists of a spring arm having one end fixed to the contact piece and its opposite end provided with a lateral shoulder removably mounted in an aperture C^6 in the arm c^3 .

The contact piece C preferably consists of a series of sections, but may consist of a single piece, as seen at Fig. 7, and, when composed of sections, suitable springs F are passed 50 through longitudinal apertures C^7 in the separated sections of the contact piece and the extremities of the springs are suitably secured to said sections. The springs F are preferably formed so that they naturally assume a 55 curved longitudinal plane and when within the apertures C^7 they tend to supplement the action of the spring presently described for forcing the contact piece against the commutator and said springs also operate to secure 60 together the sections of the contact piece. The sections c^1 c^2 of the supporting body c are somewhat separated, and are connected by a spiral spring c^5 , which operates to insure a positive contact of the contact piece with 65 the commutator. A suitable spring bar c^6 is secured to the outer side of the spring c^5 and imparts the desired stiffness thereto for pre-

venting lateral movement of the spring c^5 without unduly restraining its yielding movement toward and away from the commutator. 70 The outer end of the section c^2 may be of any desirable form to readily enter the aperture b in the corresponding brush holder B, and permit operative engagement of the brush holder clamp b' . In practice, I prefer to use 75 a lubricant upon the peripheral face of the commutator, which readily passes between the ribs of the bearing face of the contact piece without effecting its elevation and thereby impairing its metallic contact. Consequently, the peripheral face of the commutator is continually wiped and cleansed and a much better contact is afforded than would otherwise be possible.

As is well known to those skilled in the art, 80 the usual cause of sparking between a commutator and its brush is due to the retardation of the passage of the current of reverse direction when the coils leave the brush, and to obviate this undesirable result my contact 85 piece is formed with the opposite edges of its bearing face of greater resistance than its central portion. Consequently, when a coil leaves the edge of the portion of the brush of less resistance a current of reverse direction 90 is partially established but no sparking takes place as the coil is still in contact with the portion of the brush of greater resistance and when the coil leaves the latter portion of the brush, the current of reverse direction is entirely established and there is no tendency to 95 sparking. The opposite edges of the bearing face of the contact piece C may consist of the lower edges of plates C^8 suitably secured directly to the longitudinal sides of the contact 100 piece and formed of greater resistance than the interposed portion of said contact piece. I prefer, however, to form the plates C^8 of the same material as the interposed portion of the contact piece and I place non combustible 105 insulating strips c^7 between said plates and the interposed portion of the contact piece. The plates C^8 may be secured in position by suitable fastening means c^8 and the resistance of said plates may be regulated by the conductivity of said fastening means; or the fastening means c^8 may be suitably insulated from the plates C^8 as by washers c^9 and the resistance of said plates may then be regulated by conducting pins or connections c^{10} of 110 suitable resistance connected to the plates C^8 and to the interposed portion of the contact piece. 115

At Fig. 10 I have shown a modification of my invention, in which the contact piece C^{10} is formed of a single part, and the bearing face C^{11} of the body section c^{11} is substantially flat longitudinally, and is formed of rounding 120 cross section; and at Fig. 8 I have shown two sections C^{20} of a modified construction of contact piece, each section being provided with an independently movable flat spring C^{21} mounted in a transverse groove C^{22} .

At Fig. 9 I have shown a contact piece C^{30}

substantially similar to the contact piece C^{10} , and have illustrated one end of a slightly modified form of supporting body c^{30} consisting of a flat spring bar having a downwardly bent rib c^{32} arranged in the longitudinal socket or groove c^{31} of the contact piece.

At Figs. 10, 11, 12 and 13, I have shown a further modified construction of contact piece C^{40} provided with a removable wearing plate C^{41} having a transversely curved bearing face disposed in a substantially flat lengthwise plane, and a supporting body consisting of a fixed section c^{40} and a movable section c^{41} journaled upon the free end of the former section. It is thus apparent that the exact detail construction and arrangement of the contact piece and its supporting body may be somewhat varied.

From the foregoing description and the accompanying drawings it is obvious that the contact piece of my brush, when in its operative position, is capable of partial revolutions on axes arranged at substantially right angles with each other and is therefore universally movable within the limits of its partial revolutions, and readily accommodates itself to the conformation of the periphery of the commutator without liability of impairment of its contact. The brush also permits the commutator to move in opposite directions and is particularly silent in operation and is durable in use. The contact piece when worn may be readily detached and replaced by a new one, and the brush is then substantially as good as new. Moreover, the use of oil between the commutator and the brush also adds greatly to the durability of the device.

The operation of my invention will be readily perceived upon reference to the foregoing description and the accompanying drawings, and, as previously stated, it is obvious that the exact detail construction and arrangement of its parts may be somewhat varied.

Having thus fully described my invention, what I claim as new, and desire to secure by Letters Patent, is—

1. A commutator brush comprising a supporting body, and a contact piece provided with a concave bearing face for making contact with the commutator and connected to the body by a hinge-joint interposed between parallel planes extending through the projecting edges of the bearing face and substantially perpendicular to a plane projected through said edges, said hinge-joint being arranged substantially parallel with the projecting edges of the bearing face, substantially as and for the purpose specified.

2. A commutator brush comprising a supporting body, and a contact piece provided with a concave bearing face for making contact with the commutator and connected to the body by a hinge-joint interposed between parallel planes extending through the projecting edges of the bearing face, and substantially perpendicular to a plane projected through said edges, said hinge-joint being ar-

ranged substantially parallel with the projecting edges of the bearing face, and the face of said joint nearest said bearing face being arranged nearer its intermediate portion than its projecting edges, substantially as and for the purpose set forth.

3. A commutator brush comprising a supporting body, and a contact piece provided with a concave bearing face for making contact with the commutator and connected to the body by a hinge-joint interposed between parallel planes extending through the projecting edges of the bearing face and substantially perpendicular to a plane projected through said projecting edges, said hinge-joint being arranged substantially parallel with the projecting edges of the bearing face, and the face of said joint nearest said bearing face being arranged nearer its intermediate portion than its projecting edges, and a lock for normally securing the contact piece to the body, substantially as and for the purpose described.

4. A commutator brush comprising a supporting body, and a contact piece hinged to the body and having a bearing face for making contact with the commutator provided with projecting ribs extending between the front and rear edges of said face, substantially as and for the purpose specified.

5. A commutator brush comprising a supporting body, a contact piece hinged to the body and having a bearing face for making contact with the commutator provided with inclined projecting ribs formed with the front end of one rib in proximity to a transverse plane drawn through the rear end of the next adjacent rib, substantially as and for the purpose described.

6. A commutator brush comprising a supporting body provided with a bearing face formed rounding in cross section, and a contact piece having one side formed with a socket or groove for receiving the bearing face of the body and its opposite side provided with a concave bearing face for making contact with the commutator, and a lock for normally securing the contact piece to the body, substantially as and for the purpose set forth.

7. A commutator brush comprising a supporting body provided with a bearing face formed rounding in cross section, and a contact piece having one side formed with a socket or groove for receiving the bearing face of the body and its opposite side provided with a concave bearing face for making contact with the commutator, substantially as and for the purpose specified.

8. A commutator brush comprising a supporting body provided with a convex bearing face formed rounding in cross section, and a contact piece having one side formed with a socket or groove for receiving the bearing face of the body and its opposite side provided with a concave bearing face for making contact with the commutator, substantially as and for the purpose described.

9. A commutator brush comprising a supporting body, and a contact piece hinged to the body and consisting of separate sections arranged end to end, substantially as and for the purpose set forth.

10. A commutator brush comprising a supporting body, a contact piece hinged to the body and consisting of separate sections arranged end to end and provided with longitudinal apertures aligned with each other, and a spring arranged in said apertures and having its opposite ends secured to the sections, substantially as and for the purpose specified.

11. A commutator brush comprising a supporting body, and a hinged contact piece supported by the body and movable on axes arranged at substantially right angles with each other, substantially as and for the purpose described.

12. A commutator brush comprising a supporting body consisting of separate sections one of which is supported by the other and is movable independent thereof, and a contact piece hinged to the movable section, substantially as and for the purpose set forth.

13. A commutator brush comprising a supporting body consisting of separate sections one of which is supported by the other and is provided with a partially revoluble arm arranged at substantially right angles with the lengthwise plane of the body, and a contact piece provided with a bearing face for making contact with the commutator arranged substantially parallel with said arm and hinged thereto by a joint interposed between parallel planes extending through the projecting edges of the bearing face and substantially perpendicular to a plane projected through said edges, said hinge-joint being arranged substantially parallel with the projecting edges of the bearing face, substantially as and for the purpose specified.

14. A commutator brush comprising a supporting body consisting of separate sections one of which is supported by the other and is movable independent thereof, a spring for holding the movable section in its normal po-

sition, and a contact piece hinged to the movable section, substantially as and for the purpose set forth.

15. A commutator brush comprising a supporting body consisting of separate sections one of which is supported by the other and is movable independent thereof, a spiral spring for holding the movable section in its normal position, a spring bar secured to one side of the spiral spring, and a contact piece hinged to the movable section, substantially as and for the purpose described.

16. A commutator brush comprising a supporting body consisting of separate sections one of which is supported by the other and is provided with a partially revoluble arm arranged at substantially right angles with the lengthwise plane of the body, a spiral spring for holding the movable section in its normal position, a spring bar secured to the outer side of the spiral spring, and a contact piece provided with a bearing face for making contact with the commutator arranged substantially parallel with said arm and hinged thereto by a joint interposed between parallel planes extending through the projecting edges of the bearing face and substantially perpendicular to a plane projected through said edges, said hinge-joint being arranged substantially parallel with the projecting edges of the bearing face, substantially as and for the purpose specified.

17. A commutator brush comprising a supporting body, and a contact piece hinged to the body and having an outer portion of its face formed of greater resistance than the next adjacent portion thereof, substantially as and for the purpose described.

In testimony whereof I have hereunto signed my name, in the presence of two attesting witnesses, at Syracuse, in the county of Onondaga, in the State of New York, this 17th day of January, 1895.
